UNITED STATES PATENT OFFICE.

MICHAEL ZIPPLER, OF ALLEGHENY, PENNSYLVANIA.

CUPOLA-FURNACE.

No. 874,476.

Specification of Letters Patent.

Patented Dec. 24, 1907.

Application filed March 13, 1907. Serial No. 362,206

To all whom it may concern:

Be it known that I, MICHAEL ZIPPLER, a resident of Allegheny, in the county of Allegheny and State of Pennsylvania, have invented a new and useful Improvement in Cupola-Furnaces; and I do hereby declare the following to be a full, clear, and exact description thereof.

My invention relates to cupola-furnaces, and has special reference to the formation of linings in such furnaces, such as is shown in Letters Patent No. 638,541 granted to me on December 5th, 1899.

The object of my invention is to provide a simple and efficient lining for such furnaces in which a larger amount of air can be fed to the furnace through said lining than is ordinarily provided and without weakening the furnace or said lining, and a still further object of the invention is to provide for a more even and better distribution of the air fed to the furnace.

My invention consists, generally stated, in the novel arrangement, construction, and combination of parts, as hereinafter more specifically set forth and described and particularly pointed out in the claims.

To enable others skilled in the art to which my invention appertains to construct and use my improved cupola furnace, I will describe the same more fully, referring to the accompanying drawing, in which—

Figure 1 is a vertical central section of the base portion of a cupola-furnace showing my invention applied thereto. Fig. 2 is a cross-section of the same on the line 2—2. Fig. 1 and looking in the direction of the arrows. Fig. 3 is a side elevation of a portion of the furnace showing a part of the same broken away on the line 3—3 Fig. 1 and looking in the direction of the arrows. Fig. 4 is a perspective view of one of the air-boxes employed.

Like symbols of reference herein indicates like parts in each of the figures of the drawing.

As is illustrated and described in said patent the cupola-furnace is shown at A and is provided with the ordinary sheeting or casing 1 for inclosing the lining 2, which is generally formed of fire bricks and of the same general thickness of walls throughout the length or height of the furnace. The casing 1 and lining 2 of the furnace A are built up from the bottom plate 3, which rests upon columns 4 and extend down to the ground or floor of the

foundry or mill for supporting said furnace. The bottom plate 3 has an opening 5 therein which is closed by doors 6 hinged at the side of said plate and such doors form the bottom 60 or base of the furnace A for supporting the material within the same and permitting the withdrawal of said material within the furnace after the heat or when desired. At the bottom of the furnace A and adjacent to the 65 plate 3 is the ordinary top-hole 7 which extends through the casing 1 and lining 2 and is adapted to draw off the molten metal from the interior of the furnace.

In the present construction the lining 2 is built up from the bottom plate 3 for a short distance of uniform thickness to form the wall portion 8 of the lining and upon this wall is secured the lower metal ring 9 formed of segmental plates or sections. Resting 75 upon the ring 9 are a series of metal blocks 10 which are placed around said ring so as to form spaces or main flues 11 between them and the space or annular flue 12 between the rear of the blocks 10 and the casing 1 for the 80 circulation of air to the interior of the furnace A through air pipes 13 opening into the flue 12 from the main blast pipe 14 located on the exterior of and surrounding the said furnace. These blocks 10 are provided with 85 curved faces 15, which correspond to the interior curved line of the ring 9, and are also formed with the recesses 16 on the rear of the same for more properly distributing the air from the air pipes 13 to the interior of the 90 furnace. Another metal ring 17 formed in segmental plates or sections is laid or seamed upon the blocks 10 for supporting the metal bricks or plates 18 which rest by their bottom faces on the said ring and are tapered on 95 their sides to form a brick or plate of key-stone or wedgeshape for insertion to form the circular metal lining 19 at this point. The plates or bricks 18 have their front faces 20 inclined upwardly and inwardly toward 100 the center of the furnace and if desired their rear faces 21 can be recessed for the purpose of decreasing the weight of the same. Upon the top faces of the blocks 10 is the upper metal ring 22 which is formed in segmental 105 plates or sections and supports the wall portion 23 of the lining 2, while said lining portion is preferably of the ordinary fire-brick and extends from the upper inner edge of the ring 22 in a vertical line to form the inwardly projecting portion 23 of said lining. Above this projecting portion 23 the lining 2

extends backward and upward at an incline, as at 24, and joins the upper wall 25 of the lining 2 at its upper end, such portion 23 and said wall being preferably formed of fire-brick and said wall is of the usual thickness of about four and one-half inches from the portion 23 up to the top of the furnace A.

Extending up from the flues 11 and 12 are the auxiliary flues 26 which lead into the furnace A through and within the lining 2 and projecting portion 23 thereof, and these flues 26 are formed of the metal boxes 27 built within said lining and against the casing 1. These boxes form compound twy whole 15 and are preferably in two sections to provide for the vertical and the substantially horizontal and downwardly inclined passage-ways 28 and 29 respectively for forming said flues. The boxes 27 are provided with the open side 30 20 which fits against the casing 1 to form the passage-way 28, and the passage-way 29 is also provided with an open top 31 which is closed by the cover or top-plate 32 fitting over said top and held within the passageway 25 29 by the strips 32' on said plate. The vertical section 33 of the boxes 27 for the passageway 28 is preferably provided with the projection 34 at the upper end of the same for forming a seat 35, within which seat the 30 end of the inclined twy whole section 36 of said boxes are adapted to fit and be held in place by bolts or pins 37 passing through the same.

In the operation of my improved cupola-furnace A the material for melting the metal 35 is placed upon the doors 6 in the ordinary manner and such material extends up to the top of the lining 24 where the metal to be melted is placed. The fire having been started within the furnace A the air from the 40 blast pipe 14 will pass into the flue 12 and thence into the furnace A through the flues 11 and 26 which will cause the metal to melt and run down the lining 24 through the material to the bottom of said furnace and away 45 from the said flues 11 and 26 where it can be drawn off through the top-hole 7. After the metal has been drawn off through the top-hole 7, the doors 6 can be opened and the material left within the furnace A will be free 50 from the lining 2, so that it can be dropped to the ground or floor.

It will thus be seen that my improved cupola-furnace construction is cheap and efficient when installed and practical experience has proven that it will prevent the clogging of the furnace and the running of the metal into the air flues, thereby prolonging the life of the lining and the furnace and thus saving labor, time, and expense in the operation of these furnaces. It will also be seen that the use and shape of the such lining will prevent the cinder, metal, etc. from adhering thereto, as in the ordinary brick-lining, and so do away with all liability of the breaking 60 or chipping of the same during the cleaning

out or removing of said adhering substance, as in the case of brick lining, while at the same time the air is fed to the furnace at the proper points and all around the furnace where it is desired to have the same for the purpose intended. By having the twy whole portion formed separate from the vertical portion of the air-boxes the said twy whole portion and cover can be easily and quickly removed from the lining in the case of their burning out and new ones inserted, while the inclining of said twy whole portions will prevent any ashes or other material entering the same and clogging them up.

Various modifications and changes in the design and construction of my improved cupola-furnace may be resorted to without departing from the spirit of the invention or sacrificing any of its advantages.

What I claim as my invention and desire to secure by Letters Patent is—

1. A cupola-furnace having a casing, a lining within said casing formed with an inwardly projecting fire-brick or clay portion at the base thereof and having air supply flues leading through said lining into said furnace below said projecting portion, and compound twy whole in said lining and against said casing having air supply flues connecting said first named flues and leading up from the same and into the furnace through said projecting portion.

2. A cupola-furnace having a casing, a lining within said casing formed with an inwardly projecting fire-brick or clay portion at the base thereof and having air supply flues leading through said lining into said furnace below said projecting portion, and compound twy whole in said lining and against said casing having a vertical air supply flue connecting said first named flues and leading up from the same and a horizontal air supply flue connecting said vertical flue and leading into said furnace through said projecting portion.

3. A cupola-furnace having its lining formed with an inwardly projecting fire-brick or clay portion at the base thereof and having air supply flues leading up through said lining and into the furnace below said projecting portion, and compound twy whole in said lining and against said casing having a vertical passage-way leading up from said first named flues and a horizontally inclined passage-way connecting said vertical passage-way and leading into the furnace through said projecting portion.

4. A cupola-furnace having a casing, a lining formed with an inwardly projecting fire-brick or clay portion at the base thereof and having air supply flues leading through said lining into the furnace below said projecting portion, and compound twy whole in said lining and against said casing formed of metal flue boxes for connecting said flues and having a

vertical passage-way leading up from said first named flues and a horizontally inclined passage-way connecting said vertical passage-way and leading into the furnace through 5 said projecting portion.

5. A cupola-furnace having its lining formed with an inwardly projecting fire-brick or clay portion at the base thereof and having air supply flues leading through said lining into the furnace below said projecting portion, and metal flue boxes connecting said flues and formed of a vertical portion and a substantially horizontal twyer portion leading into the furnace through said projecting 10 portion and said twyer portion being removably connected to said vertical portion.

6. A cupola-furnace having its lining

formed with an inwardly projecting fire-brick or clay portion at the base thereof and having air supply flues leading through said lining into the furnace below said projecting portion, and metal flue boxes connecting said flues and formed of a vertical portion and a substantially horizontal twyer portion leading into the furnace through said projecting 20 portion, said twyer portion being inclined toward the interior of said furnace and being removably connected to said vertical portion.

In testimony whereof, I the said MICHAEL ZIPPLER have hereunto set my hand.

MICHAEL ZIPPLER.
